UNITED STATES PATENT OFFICE.

ROBERT ZAHN, OF PLAUE, GERMANY.

EMBROIDERY-FRAME-SUSPENSION DEVICE.

No. 803,656.

Specification of Letters Patent.

Patented Nov. 7, 1905.

Application filed March 3, 1904. Serial No. 196,363.

To all whom it may concern:

Be it known that I, ROBERT ZAHN, a subject of the German Emperor, residing at Plauen, in the Kingdom of Saxony and Empire of 5 Germany, have invented certain new and useful Improvements in Embroidery-Frame-Suspension Devices, of which the following is a specification.

This invention relates to an embroidery-frame suspension for embroidering-machines, wherein the frame at its two ends repose upon a lever respectively forming a rigid whole with two other levers, which at their two ends by means of tightly-stretched mechanism are 10 connected to two similar levers at the other end of the frame. This forced connection of the two carrying-levers brings about an advantage especially important with very long embroidery-frames, consisting in the fact that 15 the two ends of the frame are forced to make fully analogous movements on the frame, being driven at one end only by the pantograph.

In the annexed drawings two forms of construction of my invention are represented.

25 Figure 1 is a front view; Fig. 2, a top view of one form of construction; Fig. 3, an elevation, and Fig. 4 a side view, of the most important parts of the other form of construction.

30 In Figs. 1 and 2, *a* indicates the left front partition of the machine-frame, *b* the superior front, and *c* the superior back main longitudinal girder of the machine. Upon the front partition *a* two powerful pillow-blocks

35 *d* are fastened, carrying the shaft *e* of a band-pulley *f g* in a bearing almost totally free of friction—for instance, in a ball-bearing. This band-pulley, which upon its circumference receives the two strong steel bands *h i*, is

40 preferably constructed as shown in Figs. 1 and 2, where the pulley is not cylindrical upon its whole circumference, but, moreover, consists of cylindrical segment-pieces, and thus forms a sort of two-armed lever, referred to

45 in the preamble. By means of a suitable tension device the very strong tightening of the bands *h i* may be regulated in an easy and effective manner. This tension device consists of a threaded tension-block *k*, at-

50 tached to the end of the bands by riveting or in any other suitable manner, respectively, and may be connected to a head *l* by means of a nut and lock-nut. Rigidly connected to the band-pulley *f g* is the edged frame-carrying 55 lever *m* and the counterpoise-lever *n*. On the free end of the lever *m* the stilt *o* is arranged

in bearing also nearly fully free of friction, and upon said stilt the embroidery-frame repose or bears by means of the so-called “street” *q*, rigidly attached to it. 60

Precisely the same arrangement as above described, eventually without the counterweight *r* and lever *n*, is also provided at the right side of the machine, so that by means of the tightly-stretched bands *h* and *i* a forced 65 connection of both band-pulleys *f g* is gained. By means of this forced transmission of motion from one band-pulley to the other one the guiding of the embroidery-frame, designed as advantageous in the preamble, is brought 70 about in a very effective manner, and the slightest movements of one band-pulley are instantly and without any difference supplied to the other pulley, a result which heretofore it was impossible to attain with the means of transmission well known in embroidering-machines. 75 This advantageous effect may be explained by the fact that the two bands *h* and *i* may be chosen of such large cross-section and may be so tightened by means of the tension 80 device *k l* that the surplus load on the bands resulting from the acceleration of the masses is not able to produce any remarkable change of the bands in length, because this surplus load makes up only a small percentage of the 85 load which exists in the device when at rest and consists of the weight of the frame and its counterweight, but also is produced by the tightening of the tension-bands by means of the tension device *k l*. 90

In the device schematically shown in Figs. 3 and 4 the same letters of reference are used as in Figs. 1 and 2, so that this construction will be fully understood when referring to the latter figures. On the shaft *e*, supported in 95 the same manner as in Figs. 1 and 2, the embroidery-frame lever *m* and the counterweight-lever *n* are arranged. However, instead of the two cylindrical band-pulley segments *f* and *g* a two-armed lever *f' g'* is used, and at 100 the free ends of this lever the tension mechanism—for instance, steel wires *h' i'*—are rotatably arranged. In Fig. 3 the lever *f'' g'' m*, situated at the right side of the machine, is shown and arranged in such a manner as to 105 swing around the shaft *e*.

Having now fully described my invention, I declare that what I claim is—

1. In an embroidering-machine the combination of a frame, rocking levers supporting 110 said frame and provided with oppositely-disposed pairs of arms, metallic straps or wires

connecting said arms, securing synchronous movement of said levers, and tension devices for said wires.

2. In an embroidering-machine the combination of a frame, shafts located at opposite ends of said frame, levers mounted on said shafts having oppositely-projecting segments, metallic straps or wires connecting said segments, tension devices on said segments for

10 said straps or wires, said levers having devices supporting the frame, and a counter-weight for said frame.

In testimony whereof I affix my signature in presence of two witnesses.

ROBERT ZAHN.
